UNITED STATES PATENT OFFICE

JOHN A. DICKERSON, OF CHICAGO, ILLINOIS

CONSTRUCTION FORM

Application filed January 31, 1929. Serial No. 336,501.

The invention relates to forms such as are employed in construction work in the production of sewage systems, manholes, service tunnels, subways, culverts and conduits for various purposes.

The invention has as its principal object the provision of a form composed of a plurality of form sections which are designed to be associated with each other to produce the form and which when the form has completed its work may be collapsed and be removed from the structure for future use.

The invention further contemplates the provision of a plurality of form sections which are adapted to be arranged in a circumferential manner and to provide for the removal of one of said sections from the other of said sections so that the latter may be collapsed and be removed from the structure produced through means of the form.

In addition it is an object to connect certain of said form sections with each other and to arrange the removable form section relatively to said connected sections so that upon removal of said removable section, the connected sections may be manipulated to facilitate their removal from within the bore or opening of the conduit or other structure.

It is a further object of the invention to provide a construction having form sections, certain of which are connected with each other, so that they are movable relatively to each other, in combination with form sections which engage the first mentioned form sections and act as inserts or spacers, the last mentioned form sections being removable from between said first mentioned sections to thus allow movement of the connected sections to separate them from the construction work and permit their removal therefrom.

The invention has also as an object the utilization of means for holding said connected sections in spaced relation to each other to thereby allow the introduction and removal of the removable form section from between the connected sections.

It is also an object to shape the removable form section so that movement thereof in one direction beyond the outer faces of the completed form is prevented when associated

with the other form section, but however, is permitted to be moved in the opposite direction to accomplish its separation from the other form sections and thus permit the collapse of the completed form.

The invention has these and other objects, all of which will be explained in conjunction with the accompanying drawings which illustrate various structures which may be resorted to, it being therefore obvious that the invention is capable of other changes without departing from the scope of the appended claims forming a part hereof.

In the drawings:

Fig. 1 is a view showing the structure employed to form a conduit, the material of which the conduit is formed being shown in section.

Fig. 2 is a view similar to Fig. 1 illustrating the manner in which the elements of the form shown in Fig. 1 may be arranged to allow their withdrawal from the bore.

Fig. 3 is a plan section taken on line 3—3 of Fig. 1, showing a number of forms arranged for use.

Fig. 4 is a perspective view of a fragment of one of the elements employed in the structure illustrated in Fig. 1.

Fig. 5 is a view similar to Fig. 1 illustrating a modified structure.

Fig. 6 is a view similar to Figs. 1 and 5 of another modified structure.

Fig. 7 is a section taken on line 7—7 of Fig. 6, and

Fig. 8 is a sectional view of a further modification which may be resorted to.

When either of the various structures shown are desired to be employed to form a conduit, the various sections whereby a form is fabricated are arranged relatively to each other to produce the form, the forms thus produced being arranged end to end and connected together. The concrete is then applied to the form and after the concrete has become set or dried the form is collapsed and the several sections of each form removed from the bore of the conduit. This mode of procedure is continued until all of the forms have been removed from the conduit. By the provision of a form which is of several

sections, and the provision of means whereby the several sections may be associated with each other to produce the desired form and the provision of means whereby the form may be collapsed after the completion of its work and be re-employed, results in a material saving in the formation of conduits, etc.

The various structures illustrated for accomplishing the invention contemplates the provision of a plurality of separate longitudinally extending sections generally designated 10, 11, 12, 13, 14 and 15. These sections are adapted to be associated with each other to produce the form around which the concrete is poured.

In the structure shown in Fig. 1, certain of said sections, such as 10 and 11, 14 and 15, are connected with each other to provide the pairs respectively designated 17 and 18.

These pairs are separated from each other, when arranged to provide the form, by means of the spacers or inserts which provide form sections 12 and 13. These form sections 12 and 13 are separably held between said pairs 17 and 18 and provide means whereby the form fabricated by said several sections may be collapsed and be removed from the conduit produced by the form.

The form sections 10 and 11, and 14 and 15 in the structure illustrated are each composed of a wall portion 19 and the end frames 20 and 21 which are arranged at the opposite end of each section and provide supports for said wall sections. One form section thus formed is connected with a similarly constructed form section to thus produce the pairs 17 and 18. To produce said pairs, each of the end frames is provided with one part of a hinge connection 22, whereby said pairs may be extended to thus arrange said pairs to assist in defining the opening and to be collapsed to allow said sections to be removed from the bore or opening of the conduit after the formation of said opening. The form sections 12 and 13 are designed to be respectively located between the free ends of the hinged sections or pairs and to form part of the outline of the opening. These form sections 12 and 13 are each wedge-shaped and the terminations such as 24 of the end frames are also bevelled to correspond to the inclination of the wedge and therefore it will be evident from the following that said wedge-shaped form sections are prevented against movement in one direction, but however, are allowed to be withdrawn from between said pairs of form sections when moved in the opposite direction. The pairs of sections 17 and 18 are held in spaced relation to admit the wedge-shaped form sections 12 and 13 between them by means of the stays or supports 25 and 26, which supports also provide supports for said wedge-shaped form sections 12 and 13 to hold the latter in associated relation with the other form sections. These

supports 25 and 26 are removably secured to the respective end frames by any suitable means such as bolts 27.

It is evident from the foregoing description that after the form sections have been associated with each other to produce the form and after the concrete or other material of which the form is to be constructed has been applied and become set, that the form may be readily removed from the conduit by removing either or both of the form sections 12 and 13 from between the pairs of form sections, which will allow the hinged sections to be collapsed and removed from the bore of the conduit. To accomplish this, either one or both of the form sections or inserts 12 and 13 of the form in the formed conduit are moved endwise in an outwardly direction relatively to the endmost form in the conduit until the opposite end of said sections 12 and 13 clear the adjacent support 25 or 26, which allows this last mentioned end of said inserts or form sections to be moved inwardly toward the bore and the opposite end of said section to be removed from between said pairs of forms.

The supports 25 and 26 are then disconnected from the respective end frames, which allows the pivotally connected form sections to be collapsed and withdrawn from the bore of the finished conduit or other construction.

The sections, such as 10 and 11, may be connected together by a bar 28, which, when withdrawn from its association with the parts 22, allows each section to be separately collapsed and withdrawn from the finished structure, it being understood that the bolts 27 are removed, as previously explained, to accomplish this.

The structure illustrated in Fig. 6 discloses an arrangement whereby manholes or other rectangular bores or openings may be produced. This structure contemplates the utilization of form sections formed to produce the angular or corner form sections 29, 30, 31 and 32, which are secured together by the connecting bars or supports 33, which are bolted or otherwise secured to the end frames 34 of the form sections 29 to 32, and are provided to perform the same function as the end frames referred to in the explanation of the structure shown in Fig. 1.

Removable form sections 35 are employed in this structure which are similar in function to those shown in Fig. 1. However, in the structure shown in Fig. 6, one of these removable form sections 35 is arranged between each pair of said corner form sections. It is manifest that this arrangement also allows the completed form to be dismantled by causing the separation of the sections and in which the separate sections are held in associated relation by the key members or separable form sections 35.

The structure disclosed in Fig. 5 contemplates the utilization of separate sections

36 and the inserts 37, the supports such as 25 and 26, shown in Fig. 1, being dispensed with. A strut 38 is employed in this structure to hold the inserts in place between the 5 sections 36. The elements of the structure just referred to are held against displacement by the weight of the material of which the bore is formed by means of the circumferential wire or other bands or straps 39, which 10 are applied at intervals to the length of each form.

The structure illustrated in Fig. 8 discloses another structure for accomplishing the formation of a bore or opening. This structure 15 is particularly adapted for the formation of conduits for the reception of cables, pipes, etc., and contemplates the employment of form sections 40 and 41, and inserts or removable form sections 42 and 43, the sections 20 40 and 41 being provided with the inturned flanges 44 between which the inserts are located. These several sections are held together by means of one or more bands 45 and a core 46 is employed which, after the concrete structure has become set, is removed, 25 which allows the structure including the form sections 40, 41, 42 and 43 to be separated from each other and removed from the bore produced by the form.

30 From the foregoing description, it is evident that a simple practical structure is disclosed, whereby to form a conduit, which structure may be readily set up for use and be dismantled and be again employed.

35 What I claim as my invention and desire to secure by Letters Patent is:

1. In a form support, the combination of a plurality of circumferentially arranged sections providing form supports, means detachably connecting adjacent ends of said form supporting sections and maintaining said ends in spaced relation to each other and providing a support for said supporting sections arranged transversely of said space, a form member adapted to be arranged in said space, said last mentioned form member providing means for completing said form and providing a space into which an end of the first mentioned form supporting sections may 50 be moved to thereby allow said form sections to be separated from each other upon detachment of said connecting means and separation of said last mentioned form member from the form supporting sections, said detachable connecting means providing means for engaging and holding said last mentioned form member in said space.

2. In a form support, the combination of a plurality of circumferentially arranged 60 form supporting sections, a form member, said last mentioned form member being wedge-shaped and located between said first mentioned form supporting sections with the smaller dimension of said wedge extended in 65 an outwardly direction relatively to the form

and providing means for completing said form and providing a space upon separation from the form supporting sections into which an end of the last mentioned form supporting sections may be moved to thereby allow said 70 last mentioned form supporting sections to be separated from each other, and detachable means connecting adjacent ends of said first mentioned form supporting sections against separation and extending transversely of and engaging said wedge-shaped form members and providing means for holding said wedge-shaped form members between said first mentioned form supporting sections. 75

3. In a form support, the combination of a plurality of pairs of hingedly connected form supporting sections, detachable means extending from an end of one section for detachably connecting said end with an adjacent end of another section and holding said 80 sections against displacement, a form member, said detachable connecting means being arranged transversely of said form member and engaging a face of said form member, said last mentioned form member providing 85 means for completing said form and providing a space upon disconnection of said detachable means and removal of said form members from said form supporting sections into which an end of a form supporting section 90 may be moved to thereby allow said form supporting sections to be separated from each other. 95

In witness whereof, I hereunto subscribe my name this 29 day of Dec., A. D. 1928. 100

JOHN A. DICKERSON.
